UNITED STATES PATENT OFFICE.

JAMES SHELTON, OF TOWANDA, PENNSYLVANIA, ASSIGNOR OF ONE-HALF
TO JAMES SHELTON, JR., OF TOWANDA, PENNSYLVANIA.

STOCKING.

SPECIFICATION forming part of Letters Patent No. 691,327, dated January 14, 1902.

Application filed April 18, 1901. Serial No. 56,443. (No model.)

To all whom it may concern:

Be it known that I, JAMES SHELTON, a citizen of the United States, and a resident of Towanda, Pennsylvania, have invented certain Improvements in Stockings, of which the following is a specification.

The object of my invention is to produce in an ordinary machine for knitting tubular fabrics a shaped or fashioned stocking simulating what is known as a "full-fashioned" stocking, but having a seamless heel instead of the seamed heel in such full-fashioned stocking. This object I attain in the manner hereinafter set forth, reference being had to the accompanying drawings, in which—

Figure 1 represents part of a stocking-blank made in accordance with my invention; and Fig. 2 is a view representing the calf, ankle, and foot portion of the stocking after the same has been completed.

The ordinary process of making what is termed a "full-fashioned" stocking by narrowing operations upon a flat web, the edges of which are afterward united to form a stocking, is objectionable because of the slow and expensive method of manufacture and because of the presence of a seam in the heel portion of the stocking. The consequence is that stockings of this character are usually made abroad, where labor is cheap, the stockings produced in this country being almost entirely of the character known as "seamless" stockings—that is to say, those in which a heel and toe pockets are formed upon the knitted tube, the toe-pocket being subsequently closed by seaming together the courses of stitches at the end of the tube. The objection to this class of stockings is that the calf, ankle, and foot portions of the same are not shaped or fashioned, a seamless stocking being shaped by subjecting it to heat and pressure while stretched upon a board or former of the desired contour, so that some portions of the knitted tube are stretched while others are not. Hence it does not retain its shape after being used and washed.

My invention has therefore been designed with the view of producing upon an ordinary machine for making tubular fabric a shaped or fashioned stocking having a seamless heel.

In carrying out my invention I first pro-

duce upon the machine a tubular web, such as shown at 1 in Fig. 1 of the drawings, of a proper length for the leg of the stocking above the calf, and when this has been done 55 I change the knitting operation from round-and-round knitting to to-and-fro knitting, so as to produce a fabric having opposite selvage edges, gradually narrowing the fabric by dropping out needles at each end of the 60 set until the shaped portion 2 has been completed, proceeding then upon the remaining needles to form a straight portion 3, and then gradually bringing needles at the end of the set into action again, so as to widen the fabric 65 and produce the shaped portion 4 or narrowing and widening to produce any other desired formation of this portion of the stocking-blank. When the fabric has been widened sufficiently to form the heel portion of the 70 blank, round-and-round knitting is resumed until a tubular fabric 5 of sufficient length for the desired heel has been produced, whereupon to-and-fro knitting is again resumed and a narrow portion 6, straight portion 7, 75 and narrow portion 9 of selvage-edged web is produced or a selvage-edged web of other desired contour for the foot of the stocking results, the work when cast off of the needles 80 of the machine presenting a course of stitches at the end 10 of the blank.

In completing the stocking the selvage-edged portions 2, 3, 4, 6, 7, and 9 are united together by any available form of seaming or looping machine, so as to form the shaped 85 portions 2^a, 3^a, 4^a, 6^a, 7^a, and 9^a of the stocking, as shown in Fig. 2, the tubular portion 5 of the blank forming the seamless heel 5^a and the course of stitches at the end 10 of the blank being united by a seaming or looping machine, so as to close the toe by a transverse seam 10^a, the result being a stocking shaped as to calf, ankle, and foot in accordance with any desired contour of these parts, but having a heel without seam and therefore 95 free from this objection to an ordinary full-fashioned stocking.

In some cases the shaping of the foot or of both foot and ankle portions of the stocking may be effected by cutting a tubular web and then seaming together the cut edges; but in such cases the transverse toe-seam formed by

uniting the course of stitches at this end of the blank will be retained, the square toe thus produced without gore or seam at the side, together with the seamless heel, distinguishing my stocking from previous stockings which have been shaped by cutting the web.

Having thus described my invention, I claim and desire to secure by Letters Patent—

- 10 1. A stocking-blank having a shaped selvage-edged calf and ankle portion, tubular heel portion, and shaped selvage-edged foot portion, substantially as specified.
- 15 2. A stocking-blank having a tubular leg portion, shaped selvage-edged calf and ankle portion, tubular heel portion, and shaped selvage-edged foot portion, substantially as specified.
- 20 3. A stocking having a seamless heel portion, and a calf, ankle and foot portion composed of shaped selvage-edged webs having said selvage edges united, substantially as specified.
- 25 4. A stocking having a seamless tubular leg portion, and seamless heel portion, and a calf, ankle and foot portion composed of shaped selvage-edged webs having said selvage edges united, substantially as specified.
- 30 5. A stocking having a seamless heel portion, shaped calf, ankle and foot portions consisting of flat webs having their edges united,

and a transverse toe-seam formed by uniting a course of stitches at the toe end of the web, substantially as specified.

6. A stocking having a seamless tubular leg, a seamless heel portion, shaped calf, ankle and foot portions consisting of flat webs having their edges united, and a transverse toe-seam formed by uniting a course of stitches at the toe end of the web, substantially as specified.

7. A stocking having a seamless heel portion, calf, ankle and foot portions formed by shaped selvage-edged webs having their selvage edges united, and a transverse toe-seam formed by uniting a course of stitches at the toe end of the web, substantially as specified.

8. A stocking having a seamless tubular leg; a seamless heel portion, calf, ankle and foot portions formed by shaped selvage-edged webs having their selvage edges united, and a transverse toe-seam formed by uniting a course of stitches at the toe end of the web, substantially as specified.

In testimony whereof I have signed my name to this specification in the presence of two subscribing witnesses.

JAMES SHELTON.
